UNITED STATES PATENT OFFICE.

MEYER S. HESS, OF BALTIMORE, MARYLAND.

SHOE.

Application filed October 22, 1921. Serial No. 509,601.

To all whom it may concern:

Be it known that MEYER S. HESS, a citizen of the United States of America, residing at Baltimore, State of Maryland, has invented 5 new and useful Improvements in Shoes, of which the following is a specification.

The object of the invention is to provide a turned shoe of a construction wherein the sole may be completed prior to the turning 10 of the shoe and in such a form as to render unnecessary the subsequent introduction of a filler or insole as a means of finishing the interior of the shoe; to provide a shoe of the type indicated wherein the necessity for the 15 use of a moisture absorbent filler, or element serving as a filler or insole, to protect the foot of the wearer from contact with the rib formed by the stitch receiving groove at the inner surface of the main or outer sole may 20 be avoided; to provide a shoe of the type indicated wherein an increased thickness of the main or outer sole may be employed without preventing or increasing the difficulty of turning the shoe; to provide a shoe of this 25 type wherein an increased thickness of the main or outer sole may be secured by the supplemental use of an inferior material as compared with that of the exterior surface or layer of the main or outer sole; to provide 30 a shoe of this type having a laminated main or outer sole; to provide a shoe of this type having a main or outer sole which in proportion to its thickness is of increased flexibility in use; to provide a shoe of the type indicated 35 having a reinforcing element for the main or outer sole which is moisture non-absorbent and hence is not subject to deterioration or distortion by the moistening of the leather of the sole preliminary and 40 necessary to the operation of turning the shoe; to provide a shoe of the type indicated wherein the ultimately inner reinforcement of the main or outer sole serves as a means of reinforcing the rib formed in the construction 45 of the groove for the reception of the stitches by which the upper is secured thereto.

With these and other related objects in view as will appear in the course of the following description the invention consists in

a construction, combination and relation of parts of which a preferred embodiment is illustrated in the accompanying drawings, it being understood that changes in form, proportions and details may be resorted to within the scope of the claims without departing 55 from the principles involved.

In the drawings:—

Figure 1 is a plan view of the sole of a shoe of the turned type prior to the turning 60 thereof.

Figure 2 is a cross sectional view of the same.

Figure 3 is a cross sectional view of the same after the shoe has been turned. 65

Figure 4 is a detail view of the supplemental or reinforcing sole member as seen prior to its application to the main sole member.

Figure 5 is a sectional view showing a 70 slightly modified form of anchoring web or tape member.

Figure 6 is a plan view of a portion of the filler or inner sole element provided with the modified or continuous form of anchoring 75 web or tape member shown in Figure 5.

The main or outer sole member 10 as in the ordinary construction of turned shoes is grooved as at 11 to form the rib or feather 12 for the purpose of providing for the application of the stitches 13 which connect the upper 14 to the sole, the edge of the former occupying a position in the rabbet 15. 80

Disposed peripherally in interlocking relation with the main or outer element 10 of the sole is an inner reinforcing element 15' of pliable material adapting it to bend with the main sole element but having a rigidity or stiffness approximating that of the leather of which the main or outer sole element is 90 formed and consisting preferably of a moisture non-absorbent material such as a filler 16 of comminuted cork faced with fabric 17 of canvas or the equivalent thereof. The edges of this supplemental sole member 95 which, in reference to the inner surface of the rib or feather 12, performs the function of a filler are seated in the stitch groove, being suitably reduced or tapered as indicated at 18 for that purpose and being an- 100

chored to the rib under conditions permitting a limited longitudinal movement thereof relative to the main or outer sole element. There are various ways of accomplishing this anchoring of the filler or inner sole element of which one, shown in dotted lines in Figure 1 and in full lines in Figure 4 consists of comparatively narrow spaced webs or tapes 19 secured by stitching 20 to the under surface of the filler or sole element, looped around the edges of the latter and adapted to be engaged by the stitches 13 which serve to secure the upper to the rib of the main or outer sole element, said attaching webs or tapes being located near the front or toe end and the rear end of the filler or inner sole element, respectively and projecting laterally therefrom, so that the application of the upper attaching stitches 20 serves to place the webs or tapes and hence the filler or inner sole element under a strain transverse to the length of the shoe to hold the filler in a flat and smooth condition and prevent displacement bodily, either longitudinally or transversely. An alternative form of the attaching or anchoring means for the filler or inner sole element, however, is shown in Figures 5 and 6, wherein a web or tape 19' secured by stitching 20' or any preferred equivalent means, extends continuously around the side and toe edges of the filler or inner sole element and projects beyond said edges to lie in contact with the inner surface of the rib or feather 12 for engagement as in the previously described form by the stitches 13 which connect the shoe upper to the main or outer sole and hold the edges of the upper in the rabbet 15, the purpose and operation of the continuous web or tape being identical with those of the independent or separate webs or tapes, previously described and which in common with the continuous web or tape may be referred to as a marginal flexible web or tape member.

45 The supplemental filler or sole element 15' is positioned with its edges in the stitch receiving groove 11 prior to the stitching of the upper to the sole, and with the web or tape member 19 or 19', preferably arranged as shown doubled or looped upon themselves from the under surface of the supplemental sole element to which they are attached in contact with the inner surface of the rib 12 to which for convenience in positioning the parts and holding the supplemental sole member in place during the stitching operation may be adhesively secured to said inner surface of the rib, and as the upper is stitched to the sole the stitches pass through the web or tape member and thus permanently and securely anchor the inner supplemental sole member against bodily displacement relative to the main or outer sole element.

Having completed the operation to this point the rib 12 may be cemented or adhe-

50 sively secured in the position indicated in Figure 2 in contact with the exposed surface of the inner or supplemental sole element to complete the interlocking relation of the inner and outer sole elements, after which the shoe as in the ordinary practice may be softened by moisture and turned to cause the parts to assume the positions indicated in Figure 3 wherein a smooth and unbroken inner surface is presented for the reception if desired of a sock lining or the equivalent thereof which, however, being commonly used in the art is not herein shown.

55 The attachment of the inner or supplemental sole member to the outer or main sole element while ensuring a permanence of the relative positioning of these parts provides for a relative longitudinal yielding or sliding movement thereof which facilitates the turning of the shoe, so that as described a shoe may readily be turned whereas if provided with a single piece or single layer sole of the thickness of the combined outer and inner sole elements it could not be turned. The arrangement indicated provides thus for the construction of a turned shoe with a heavier or thicker sole than has heretofore been possible, and also provides for utilizing as the inner or reinforcing filler or sole element a material of an inferior grade so far as cost is concerned, and yet by utilizing for such inner or supplemental filler or sole element a material which is non-absorbent, the moistening thereof in the preparation of the shoe for the turning operation does not result in deterioration or distortion, and after the shoe has been turned a smooth and unbroken interior surface is presented.

60 The material suggested as that suitable in the construction of the inner or supplemental filler or sole member, moreover is adapted to resist the moisture incident to the wearing of the shoe and insures a permanently smooth interior surface as distinguished from that which is presented in the use of inner soles or fillers of paper or paper compositions, now in common use in this connection, which are inserted after the shoe has been turned, and which can not be inserted prior thereto and which therefore can not be anchored positively to the outer sole as in the construction herein set forth, because of the injurious effect thereon of the moistening which is necessarily incident to the turning of the shoe.

65 Having described the invention, what is claimed as new and useful is:—

70 1. A turned shoe having a laminated sole 75 consisting of inner and outer layers of relatively stiff material which is bendable on transverse lines to permit of turning, the latter having a rib and groove, and the peripheral edge of the former being fitted in 80 the groove in contact with the base of the 85

rib, and provided with spaced flexible attaching tabs secured to the rib.

2. A turned shoe having a laminated sole consisting of inner and outer layers of relatively stiff material which is bendable on transverse lines to permit of turning, the latter having a rib and groove, and the peripheral edge of the former being fitted in

the groove in contact with the base of the rib, and provided with spaced flexible attaching tabs engaged by the upper attaching stitches. ¹⁰

In testimony whereof he affixes his signature.

MEYER S. HESS.
